US00D788077S

(12) **United States Design Patent** (10) **Patent No.:** **US D788,077 S**
(45) **Date of Patent:** **** May 30, 2017**

(54) **WIRELESS REMOTE CONTROL**

(71) Applicant: **SIMU**, Gray (FR)

(72) Inventor: **Jean Ducret**, Valay (FR)

(73) Assignee: **SIMU**, Gray (FR)

(**) Term: **15 Years**

(21) Appl. No.: **29/535,753**

(22) Filed: **Aug. 10, 2015**

(30) **Foreign Application Priority Data**

Feb. 13, 2015 (WO) DM/085580

(51) **LOC (10) Cl.** **14-03**

(52) **U.S. Cl.**

USPC **D14/218**

(58) **Field of Classification Search**

USPC D14/217-218, 188, 225, 205, 155;
D13/168; D21/566, 333; D10/104.1,
D10/106.2

CPC . H05K 5/03; H04B 10/00; H01H 9/02; G09G
5/00; G09D 1/10

See application file for complete search history.

(57) **CLAIM**

The ornamental design for a wireless remote control, as shown and described.

DESCRIPTION

FIG. 1 is a perspective view of a wireless remote control according to my invention;

FIG. 2 is a front view thereof;

FIG. 3 is a left view thereof;

FIG. 4 is a right view thereof;

FIG. 5 is a rear view thereof;

FIG. 6 is a bottom view thereof; and,

FIG. 7 is a top view thereof.

The broken lines in the drawings represent portions of the wireless remote control that form no part of the claimed design.

1 Claim, 3 Drawing Sheets
